HEAD AND BATTEN STOP MOTION
ATTACHMENT FOR LOOMS

J C. Case, Lynn, N. C.

Application November 27, 1951, Serial No. 258,432

8 Claims. (Cl. 139—336)

1

This invention comprises novel and useful improvements in the head and batten stop motion attachment for looms and more specifically pertains to a stop motion attachment which will automatically stop the operation of a loom when the loom jumps time.

The primary object of this invention is to provide a stop motion which is operatively connected to the batten of the loom and to the pattern cylinder for the Jacquard type of loom for automatically stopping the loom when the head motion and the batten fail to operate in properly timed relation.

The mechanism by which the loom is stopped may be of various types, one suitable mechanism being illustrated by way of example only, in the accompanying drawings, wherein:

Figure 1 is an end elevational view of a portion of a conventional loom showing the stop motion of the present invention applied thereto;

Figure 2 is a fragmentary somewhat diagrammatic elevational view of a portion of the front of a loom showing the stop motion applied thereto;

Figure 3 is an enlarged elevational view of the stop motion attachment of this invention, taken from the front;

Figure 4 is a vertical horizontal sectional detail view taken substantially upon the plane indicated by the section line 4—4 of Figure 3;

Figure 5 is a further horizontal sectional detail view taken substantially on the plane indicated by the section line 5—5 of Figure 3;

Figure 6 is a rear elevational view of the attachment of Figure 3;

Figure 7 is an enlarged end elevational view of the attachment of Figure 3 taken from the right side thereof, the mounting of the attachment upon a portion of the loom being indicated in dotted lines therein;

Figure 8 is an end elevational view of the attachment of Figure 3 taken from the left side thereof, the manner in which the attachment is secured to a portion of the loom being indicated in dotted lines therein;

Figure 9 is a view similar to Figure 3 but showing the manner in which one of the elements of the stop motion is effective to cause stoppage of the loom; and,

Figure 10 is a view similar to Figure 9 but showing the manner in which another of the elements of the stop motion mechanism is effective to cause stoppage of the loom.

Reference is now made more specifically to the accompanying drawings, wherein like numerals designate similar parts throughout the vari-

ous views, the numeral 10 indicating a portion of the frame work of a conventional form of loom which includes a batten indicated generally by numeral 12 provided with top and bottom beams 5 14 and 16 and having a reed lay 18. The reed lay is given an arcuate backward and forward motion by means of a connecting rod 20 and driving wheel 22 in accordance with well known practice, while the batten 12 is vertically reciprocated by the usual rockers operated by the loom side motion, not shown.

In looms of this character, a head motion is provided for timing all operations of the loom. This timing starts with the usual Jacquard pattern cards which have motion holes to control all operations of the loom, the head motion operating the loom side motion which in turn operates the rockers to reciprocate the batten. If for any reason, however, the head motion fails to operate in properly timed relation to the movement of the batten series defects in the weaving of the loom and damage to the mechanism of the loom invariably results. The present invention is designed to provide an apparatus for detecting the lack of proper operation and coordination of the head and batten mechanisms and for stopping the loom when this condition results.

The present invention is mounted upon a plate or panel 24 of any suitable material which constitutes a support base, and which as shown in Figures 3 and 6 may conveniently be L-shaped. This plate or support base is detachably mounted as by fasteners 26 in the form of bolts and nuts, see Figures 2, 7 and 8, to the frame 10 of the loom adjacent the head mechanism of the same.

The L-shaped panel is preferably mounted in a position to have its legs disposed vertically and horizontally. A pair of L-shaped rods comprising slides, indicated at 28 and 30 are slidably mounted upon the base 24. The slides have vertical and horizontal portions or members 32, 34 for the slide 28 and 36, 38 for the slide 30, these slides constituting the essential detecting elements of the stop motion for actuating the same as set forth hereinafter.

A vertically disposed guide bracket indicated generally by the numeral 40 is mounted upon the outer end of the horizontal or lower portion of the support panel 24, and as shown in Figure 7 comprises a pair of parallel horizontal leg members 42 and 44 having a pair of parallel vertically disposed guide rods 46 and 48 integrally secured thereto. The legs 42 and 44 are provided with fastening nuts 50 screw threadedly engaged thereon whereby the guide bracket 40 is secured

to the panel. The horizontal leg 34 of the slide 28 is disposed in the vertical guiding slot between the member 48 and the adjacent surface of the panel 24, while the horizontal leg 38 of the slide 30 is disposed between the guide rods 46 and 48 and are thus vertically slidable between the upper and lower legs 42 and 44, and are capable of independent tilting motions therein as shown by examining Figures 3, 9 and 10.

Upon the vertical portion of the panel 24 there is provided a pair of guide hooks 52 and 54 which are disposed on opposite sides of the slide 28 and are spaced vertically therealong as shown clearly in Figure 3. The arrangement of hooks is such that pivoting movement of the L-shaped slide 28 in a counterclockwise direction as shown in Figure 3 is prevented, but a clockwise pivoting movement is possible as will be seen by comparing Figure 9 with Figure 10. To the upper end of the slide 28 is secured a cable 56 by which the slide is vertically reciprocated upon the panel for a purpose which will be later set forth.

Secured to the horizontal leg of the panel 24 on the opposite end thereof from the guide bracket 40, see Figures 3, 5, 8-10, is a guide strip 58 upon which is mounted a guide bracket 60. The space or slot between the bracket 60 and the guide strip 58 is disposed in parallel arrangement to the space between the members 46 and 48 of the guide bracket 40 and with the latter space constitutes a guide slot in which is vertically reciprocable the horizontal leg 38 of the slide 30. It will be observed that the slide 36 and the horizontal leg 38 are spaced outwardly of the panel 24 from the slide 28 with its horizontal leg 34, the slides 28, 30 thus lying and moving in parallel vertical planes, so that no interference between these slides will be possible during their sliding and tilting movements.

The slide 30, at the junction of the vertical and horizontal legs 36 and 38, is provided with an apertured lug 62 and the end of a cable 64 is secured thereto by which the slide is vertically reciprocated upon the panel for a purpose to be subsequently made apparent.

As seen from Figure 6, the lower corner of the support panel 24 is provided with a notch or cutaway portion as at 66 and a stub axle 68 is fixedly secured to the panel upon what may be termed its rear side, that is, upon the side opposite the brackets 60 and 40, this stub axle being secured by welding as at 70 and extending into the notch 66. A guide pulley 72 is journaled upon the stub axle and retained thereon by a threaded nut 74, and the above mentioned cable 64 extending downwardly from the lug 62 is entrained over this guide pulley and from thence extends upwardly behind the back side of the panel as will be seen from Figures 2, 6-8.

Referring now to Figure 2, it will be seen that the cables 56 and 64 are respectively entrained over further guide pulleys 76 and 78 which are respectively carried by support brackets 80 and 82 detachably secured on the frame 10 of the loom and are then positioned horizontally across the top frame of the loom and after passing over further guide pulleys 84 and 86, respectively, extend upwardly and are attached to the customary Jacquard cards and control the head motion of the loom. Thus, the cables 56 and 64 will be moved in synchronization with the head motion to cause vertical reciprocation of the slides 28 and 30 in synchronization therewith.

It will be noted that the horizontal leg 38 of the slide 30 is provided with a collar 88 fixedly

secured thereto which is adapted to bear against and abut the left hand side of the guide 40, as viewed in Figure 3. This collar prevents sliding movement of the horizontal leg 38 towards the right, although movement toward the left is possible.

Between the guide brackets 60 and 40, the horizontal leg 38 has secured thereto in a desired manner a tension spring 90 whose upper end is fastened in any desired manner to the support panel 24. It will be noted, as viewed in Figure 3, that the upper end of the spring 90 is disposed above and slightly toward the right of the fastening of the spring upon the horizontal arm, whereby the tension of the spring will both pull the slide upwardly, and also urge the leg 38 of the slide towards the right, with the collar 88 in sliding abutting engagement with the guide bracket 40.

20 The vertical arm 36 of the slide 30 is slidably received beneath two L-shaped slide hooks 92 and 94 which are mounted upon the support panel with horizontal supporting legs and lateral arms extending over the adjacent vertical edge 25 of the panel. The vertical leg 36 of the slide 30 lies outwardly of, or against the left side of the legs of the hooks 92, 94, as shown in Figures 3, 9 and 10, this arrangement preventing tilting of the slide 30 in a clockwise direction as 30 viewed in Figure 3, but permitting counterclockwise tilting as shown in dotted lines in Figure 3 and in Figure 9.

Secured to the vertical leg of the support panel 24 and preferably slightly above the guide hook 35 92, is a laterally extending guide strip member 96 which is welded or otherwise secured to the front surface of the panel 24 and extends laterally beyond the edge thereof. The top surface of the strip lies in the same vertical plane as 40 the top surface of the guide member 58 and of the guide surface of the guide rod 48, and with those members serve to slidably support the undersurface of the slide 30, engaging its vertical and horizontal legs 36 and 38 respectively. 45 The member 96 extends sufficiently laterally and outwardly from the support panel 24 to guide and support the guide 30 when the latter is in a tilted position as shown in dotted lines in Figure 3 and Figure 9.

50 Welded or otherwise fixedly secured to the front surface of the support panel 24 and between the slide hooks 92 and 94 are a pair of parallel supporting lugs each indicated by the numeral 98. A lever 100 is pivoted to the lugs 55 98 therebetween, and has pivotally attached to its opposite ends an actuating link 102 and a cable 104. The link 102, see Figure 4, is pivotally attached to one end of a lever 106 which extends through a slot 108 in the support panel 60 24 and is pivoted intermediate its extremities to this panel as by pivot pin 110. By means of the hook fastener 112 secured to the same end of the lever 106 as the link 102 but at the opposite side thereof, a cable 115, see also Figures 1, 2 and 9, connects the levers 106 and 100 with a loom stop motion 117 which may be mounted upon the front of the loom frame 10 and may be of the type and construction set forth in my prior co-pending applications Serial Nos. 208,345 and 214,377, filed January 29, 1951, and March 7, 70 1951.

75 The cable 104 may extend to any convenient location, as to the rear of the loom, and comprises manual operating means for the levers 100 and 106.

The lever 100 is positioned immediately adjacent the vertical leg 36 of the slide 30, as will now be apparent from Figures 3, 4, 9 and 10. Consequently, tilting or lateral movement of the vertical leg 36 from the full line to the dotted line positions shown in Figures 3 and 9 will be effective to displace the lever 100 to the left as viewed in Figure 4, thereby through the link 102 causing pivoting movement of the lever 106, movement of the cable 115 and actuation of the stop device 117.

The lever 106 as also shown in Figures 3, 4, 9 and 10 is disposed adjacent the vertical leg 32 of the slide 28, the arrangement being such that when the slide is tilted, as shown in Figure 6, its vertical leg 32 will press against the lever 106 and tilt the same. This tilting of slide 28 will cause link 102 to pivot lever 100 thereby actuating the stop motion 117.

As so far described, it will be apparent that the tilting movements of either of the slides 28 and 30 will thus be effective to tilt the lever 106 in a clockwise direction as viewed in Figure 4 and thereby actuate the stop motion 117.

On the rear side of the panel 24 as shown more clearly in Figures 4, 6, 7 and 8, the upper end of the lever 106 is attached to a link 113, which in turn is connected with an electric switch 114 of any suitable design and forming part of the electric power circuit of the loom. It will thus be apparent that upon actuation of the lever 106, the switch will be actuated in turn, and in any desired manner will stop the operation of the loom. As hereinbefore set forth, the cable 104 comprises a manual means actuatable remotely, for stopping the loom by tripping the switch 114 or the stop motion 117.

Referring now again to Figure 1, it will be seen that the stop motion attachment of this invention is mounted upon the frame of the loom in such a manner that the horizontal legs 38 and 34 of the slides 28 and 30, are disposed respectively between the top and bottom beams 14 and 16 of the batten 12, and between the bottom beam 16 of the batten and the reed lay 18. In this position, the vertical motion of the batten and the arcuate horizontal and vertical motion of the reed lay will cause the members 14, 16 and 18 to move both vertically with respect to the horizontal legs of the slides. By the cables 56 and 64, the slides are likewise caused to move vertically in timed relation to the vertical component of the batten motion so that no pressure is applied to the horizontal legs by the motion of the batten, when the head motion and batten are properly synchronized. However, if for any reason the head motion of the loom fails to function as called for by the pattern cards, there will be corresponding failure of the cables 56 and 64 to vertically reciprocate the slides 28 and 30. Consequently, the vertical component of motion of the batten will then tilt whichever of the slides is not vertically reciprocated in timed relation thereto, thereby causing through the tilting of that slide actuation of the switch 114 and of the cable 115 and stop motion 117 to thereby stop the operation of the loom.

The operation of the loom with this head and batten stop motion attachment applied thereto is as follows: The cable 56 is pulled up by the hooks of the Jacquard head and as the blades of the Jacquard head raise and lower, the hooks of the Jacquard head rise and fall, lifting the slide 28 and permitting the same to drop in synchronization or timed relation to the rise and fall of

the batten by the rockers and side motion. While the head and batten and reed lay are on time, the batten bar 16 does not apply pressure to the horizontal leg 34 of the slide 28 and therefore the latter reciprocates vertically without tilting.

If the head and batten get out of time, so that the batten does not raise at the time required by the head motion, which at the required time raises the slide 28, the stationary batten bar 16 will apply a downwardly and a clockwise tilting pressure to the upper surface of the vertically ascending leg 34, which will tilt the slide 28 to the position shown in Figure 10, thus actuating the lever 106, which through link 113 will actuate the switch 114 and through cable 115 will actuate the stop motion 117 to stop the loom.

Referring next to the cable 64, it will be understood that the same likewise is raised and lowered by loom head as set forth in connection with the cable 56 but controls the operation of the loom when the batten is to descend. Thus, the cable 64 pulls the slide 30 down against the return spring 90 when the head motion requires the batten to descend. When the head and batten are properly timed, both the leg 38 and the batten rods 14 and 16 descend together and therefore no pressure is applied to the underside of the leg 38 by the batten bar 16. However, if the batten fails to descend, as required by the head cylinder, the leg 38, descending as required by the head cylinder will engage the stationary batten bar 16. This will apply upward pressure to the leg 38, tilting the slide 30 in a counterclockwise direction as shown in dotted lines in Figures 3 and 9, thereby pivoting lever 100 which stops the loom in the manner previously set forth.

It is evident that this mechanism can be applied on various convenient portions of the loom frame since the flexible cables 56 and 64 will permit easy attachment of the mechanism to the head motion of the loom.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

Having described the invention, what is claimed as new is:

1. A stop motion for looms comprising a support, slides mounted on said support and adapted to engage the batten of a loom, guide means on said support limiting said slides to vertical movement and tilting movement in one direction from the vertical, means actuated by tilting motion of one of said slides for stopping operation of a loom, means connecting said slides to the head motion of a loom for preventing tilting of said slides.

2. A loom stop motion comprising a pair of slides operatively engageable with the batten of a loom, means for causing reciprocation of said slides actuatable by the head motion of a loom, means causing tilting of said slides by the loom batten upon failure of said slides to reciprocate in timed relation to said head motion, means operable upon tilting of said slides for causing stopping of said loom.

3. The combination of claim 1 wherein said slides comprise L-shaped members, end member being mounted on said support with its legs dis-

posed vertically and horizontally, the horizontally disposed legs being operatively engageable by a loom batten.

4. The combination of claim 2 wherein said first means comprises a cable connected to each of said slides and to the head motion of a loom.

5. The combination of claim 1 wherein said slides comprise L-shaped members, end member being mounted on said support with its legs disposed vertically and horizontally, the horizontally disposed legs being operatively engageable by a loom batten, said means for causing stoppage of a loom including a switch, a lever connected to said switch, said lever being positioned adjacent one of said slides whereby tilting of the latter will actuate the lever and operate the switch.

6. The combination of claim 1 wherein said slides comprise L-shaped members, end member being mounted on said support with its legs disposed vertically and horizontally, the horizontally disposed legs being operatively engageable by a loom batten, said means for causing stoppage of a loom including a switch, a lever connected to said switch, said lever being positioned adjacent one of said slides whereby tilting of the latter will actuate the lever and operate the switch, a second lever linked to said first lever, said second lever being positioned adjacent the other slide whereby tilting of the latter will cause actuation of the switch.

7. The combination of claim 1 wherein said slides comprise L-shaped members, end member being mounted on said support with its legs dis-

posed vertically and horizontally, the horizontally disposed legs being operatively engageable by a loom, said means for causing stoppage of a loom including a switch having an operating lever connected thereto, a second lever linked to said first lever, a slide being positioned adjacent said second lever whereby tilting of the slide will actuate the levers and the switch.

8. A loom stop motion comprising a support panel having means for mounting the same upon a loom, a pair of slides on said panel, each slide including vertical and horizontal members, said horizontal members being adapted to extend into the path of travel of a loom batten, connecting means for each slide for securing the latter to the head motion of a loom, guide means for each slide allowing vertical movement and tilting of the slides in one direction but preventing tilting in the opposite direction, whereby the horizontal members of the slides will be engaged by a batten and the slides tilted when the connecting means fail to reciprocate the slides in predetermined timed relation to the head motion, operating means actuated by tilting of the slides for stopping the loom.
